TIE CLASP WITH INTERCHANGEABLE SLIDES

Naseeb B. Baroody, Jr., Florence, S. C.

Application August 10, 1951, Serial No. 241,277

1 Claim. (Cl. 41—10)

1

The present invention relates to certain new and useful improvements in changeable type tie clasps and has more particular reference to a sectional construction which is characterized by distinctive interchangeable slides, making it possible to change the over-all appearance of the clasp at will and more or less to suit the discretion of the wearer.

It is a matter of common knowledge that men who are discrete in respect to wearing apparel follow the practice of wearing necktie holders of varying styles and designs, depending more or less on the color combinations of the shirt, necktie and suit worn at any given time. This practice, obviously, necessitates having a supply of selectively usable necktie bars or clasps constantly on hand. In the circumstances, it is believed that there has long been a practical and recognized need for a multipurpose necktie bar or clasp. It is therefore the object of the instant invention to provide a construction which is unique in that it utilizes a bar-like sheath or an equivalent receiver having at least one transparent side or panel and adapted to selectively receive and contain readily insertable and removable inserts or slides. The slides are suitably ornamented and are made up of various color combinations and by using a clear transparency in the sheath and a colorful slide or insert in association therewith, the user may adapt the thus contrived necktie bar to any and all shirt and tie combinations, as he sees fit.

More specifically, the invention has to do with an open-ended slide-containing and enveloping sheath which is preferably made of clear commercial plastics. The slide is insertable and removable in respect to the single open end of the sheath and means is provided to effectively hold the slide in its display or usable position.

Another and more general object of the invention is to structurally, functionally and otherwise improve upon similarly constructed and functioning prior art constructions, to provide a structural adaptation which is unique, reliable, and constitutes an innovation in which manufacturers, retailers and users will find their respective requirements and needs appropriately met.

Other objects and advantages will become more readily apparent from the following description and the accompanying sheet of illustrative drawings.

In the accompanying sheet of drawings, wherein like numerals are employed to designate like parts throughout the views:

Figure 1 is an exploded perspective view showing

2

ing a tie bar or so-called tie clasp constructed in accordance with the principles of the present invention.

Figure 2 is an elevational view of the parts in assembled, ready-to-use relationship.

Figure 3 is an edge elevation of the structure shown in Figure 2 and illustrating with particularity a suitable shirt clasp or an equivalent retainer.

10 Figure 4 is an enlarged view of a fragmentary nature, partly in section and partly in elevation, and showing the retaining means for releasably maintaining the slide in the sheath.

15 Figure 5 is a view showing the manner in which 15 the tie clasp is actually applied and worn by a user.

Figure 6 is a perspective view of a modified form of the invention.

20 Referring now to the drawings by reference numerals and lead lines, it will be seen (Figures 1-4, inclusive) that the case or sheath, the principal unit of the two-part combination, is denoted by the numeral 8. Though this may be of some other geometrical form or configuration, 25 it is preferably rectangular and takes the form of a transparent case which is closed at one end and open at the opposite end. At least one wall or panel is in the form of a clear transparency, as denoted at 10. In actual practice, it has been 30 found expedient and practicable to construct the sheath from clear commercial plastics, and therefore all of the sides or walls are transparent. There is a closing cap 12 fitting over the closed end, and this is of sheet material and has a score line 14 so that it appears as though it were 35 made up of two components, this for sake of symmetry in over-all appearance. There is a collar-like metal or equivalent finishing and ornamenting band 16 around the open end of the sheath.

40 The transverse end portions of this are struck out to provide resilient tongues, and the tongues are bent to form retaining latches 18, as shown in Figure 4. The insert or slide is a simple, readily applicable and removable filler or panel for

45 the sheath, and this is denoted by the numeral 20. It comprises a plastic or equivalent member 22 which is appropriately ornamented. For sake of illustration, the numerals 24 designate color bars. It is obvious that the insert could be all of one color or a combination of colors, or in some other manner ornamented to be unique and colorful. At the left-hand end, the insert is provided with a sheet metal or equivalent closure and retaining head. The main head or closure 50 part is denoted by the numeral 26 and the re-

duced portion at 28, the latter having detents 30—30 which engage releasably with the latches in the manner shown in Figure 4. When 28 telescopically snaps into the banded portion of the sheath, it is held in place by the latches with the head portion 26 conforming with the band 16 to provide an ornament at this end of the tie clasp which corresponds to the closing cap 12 at the opposite end. This provides the desired symmetry factor previously mentioned. Incidentally, the part 28 may be of plastic or may be a complement of the head 26. The main idea is to have the head 26 abutting the band or collar 16 and to provide means for latching the slide or panel 20 removably in the transparent encasing 15 sheath. With the slide in the sheath in the manner shown in Figure 2, the two parts combine into a unitary assemblage which provides a colorfully distinct bar for use in a tie clasp construction. Insofar as the clasp is concerned, it is of incidental importance. In other words, any suitable means may be provided for holding this composite, changeable type bar in place. As shown in Figure 3, there is a bracket 32 and a pivoted gripping lever 34 having its trip or handle portion 36 pivoted in the bracket bearings. Any holding means other than that shown in this figure could, of course, be used. The principal novelty in this case is directed to the open-ended sheath or equivalent transparent case and the interchangeable, insertable and removable color slides or equivalently ornamented slides and any appropriate means for fastening the slide in the sheath or case.

Reference being had to Figure 6, the modified form of the invention embodies the same general principles already revealed. Here the transparent sheath is denoted by the numeral 38 and has an ornamental or equivalent metal or the like closing cap 40 at one end. The opposite end of the tubular body of the sheath is reduced in cross-section and suitably thinned down to provide an extending neck 42 which accommodates the readily applicable and removable friction-retained closing cap 44. The neck is provided with niches as at 46 to render the coating end portion of the insertable and removable slide 48 accessible. The slide is also of commercial plastics or equivalent material and is formed with color bands or equivalent distinguishing and ornate features.

It is believed that the generic and species aspects of the invention revealed in the drawings will be clear upon studying the various views of the drawings in conjunction with the specification, and particularly in relation to the following claim.

Minor changes in the shape, size and arrangement of parts may be resorted to in actual practice without departing from the spirit and scope of the invention as claimed.

Having described the invention, what is claimed as new is:

A composite necktie bar the appearance of which may be selectively changed according to the user's attire and discretion comprising a sheath, the obverse side of said sheath being transparent, said sheath having an ornate closure at one end and being open at the opposite end, and means whereby the over-all appearance of the complete bar may be varied and changed according to the will of the user, said means characterized by a slide fitting removably in said sheath, said slide having a given color and ornamental finish, being commensurate in size with the receptacle portion of said sheath and having closure means for the open end of the sheath which is symmetrical in shape and appearance with the closure at the opposite end of said sheath, said sheath being a substantially rigid plastic tube rectangular in cross-section and of a length to match the width of the wider apron of a necktie, said closure at said one end being a cap, said slide being likewise rectangular in cross-section and fitting snugly into said receptacle portion and the closure means thereon being in the form of a cap.
